CLOTHESLINE PROP

Basil Norman Smith, Corpus Christi, Tex.

Application September 26, 1938, Serial No. 231,809

6 Claims. (Cl. 248—353)

My invention relates to supporting devices and more particularly to the class known as clothesline props.

One of the principal objects of my invention 5 is to provide a clothesline prop equipped with means for reliably securing a clothesline or the like to the upper end of the prop whereby to eliminate undesired detachment of the prop from the line and resultant dropping or sagging of the 10 line and accompanying contact of the clothes carried thereon with the ground.

Another object of my invention is to provide 15 a device of the character described which is simple in construction, durable in use, efficient in operation and economical in manufacture.

Other objects and advantages will be apparent from the following description, appended claims and annexed drawing.

Referring to the drawing wherein like reference characters designate like parts throughout the several views:

Figure 1 is a side elevation of a clothesline prop constructed in accordance with my invention.

25 Figure 2 is an end elevation of the upper end of said clothesline prop.

Figure 3 is a side elevation of said upper end of said prop.

30 Figure 4 is a sectional view taken on the line 4—4 of Figure 2.

Figure 5 is a sectional view taken on the plane of the line 4—4 of Figure 2, but illustrating the clothesline removed therefrom and the parts in disconnected position.

35 Figure 6 is a detail sectional view taken on the line 6—6 of Figure 4.

In practicing my invention I provide a clothesline prop or pole 5, the lower end of which is fashioned with a ground penetrating section 6. 40 The upper end of the prop is inwardly tapered and provided with a top face 7 formed with a downwardly extending cul-de-sac 8 terminating an appreciable distance below the face 7 as clearly illustrated in Figures 4 and 5 of the drawing.

45 One side of the prop 5, subjacent the top thereof is formed with an inwardly and downwardly extending cuneiform shaped slot 9, the upper and lower walls of which are of an arcuate configuration and effect connection with each other at their inner ends. The inner end section of the slot 9 effects transverse communication with the cul-de-sac 8 and permits a section of a clothesline 10 to extend transversely therethrough 50 as clearly illustrated in Figure 4.

Pivotedly mounted in the lower end of the cul-de-sacs, by means of a pin 11, is the lower end of a coil spring 12, the upper end of which is fashioned with a looped section 13 overlying the clothesline 10 and formed with a finger piece 5 14 extending outwardly through a longitudinally extending slot 15 communicating with the cul-de-sac 8 and slot 9. The upper end of the prop 5 is provided with a cap 16 effecting closure of the upper end of the cul-de-sac to prevent the 10 entrance of foreign matter and the like therein.

In use, the spring is extended upwardly to a position wherein the finger piece 14 is disposed above the upper end of the slot 15 as clearly illustrated in dotted lines in Figure 5. In this position the clothesline is inserted through the open end of the slot 9 and seated within the inner end thereof whereupon the spring is released, permitting the section 13 to overlie said clothesline and maintain the latter clamped 20 transversely through the upper end of the prop as illustrated in Figure 4.

From the foregoing it will be apparent that I have provided a simple and effective means for 25 securing clothesline to props to preclude undesirable disengagement of the props from said lines.

What I claim is:

1. A device of the character described, comprising a prop having an upper end section formed with a vertically disposed cul-de-sac, said section fashioned on one side thereof with an arcuate and cuneiform shaped slot effecting communication with said cul-de-sac and adapted to receive therethrough a portion of a clothesline in transverse relation relative to said cul-de-sac, and a coil spring mounted within said cul-de-sac and having an arcuate-shaped end section adapted to overlie said clothesline and maintain the latter clamped within said slot. 30 35 40

2. A device of the character described, comprising a prop having an upper end section formed with a vertically disposed cul-de-sac, said section fashioned on one side thereof with an arcuate and cuneiform shaped slot effecting communication with said cul-de-sac and adapted to receive therethrough a portion of a clothesline in transverse relation relative to said cul-de-sac, a coil spring mounted within said cul-de-sac and having a section adapted to overlie said clothesline and maintain the latter clamped within said slot, and a finger piece formed on said end section of said spring and terminating outside of said prop for exterior operation to 50 55

effect attachment and detachment of said clothesline within said slot.

3. A clothesline prop having an upper end section formed with a vertically disposed cul-de-sac, said section fashioned on one side thereof with an arcuate and cuneiform shaped slot effecting communication with said cul-de-sac and adapted to receive therethrough a portion of a clothesline in transverse relation with respect to said cul-de-sac, said upper end section formed with a vertical slot communicating with said cul-de-sac and said first mentioned slot, and a coil spring mounted within said cul-de-sac and having an upper end section adapted to overlie said clothesline and maintain the latter clamped within said first mentioned slot, said upper end section of said coil spring formed with an outwardly terminating finger-piece operable through said vertical slot to effect attachment and de-

tachment of said clothesline within said first mentioned slot.

4. The elements of claim 1 as set forth and defined therein including, a closure cap fixed to said upper end section and closing the upper 5 end of said cul-de-sac to prevent the entrance of foreign matter and the like therein.

5. The elements of claim 2 as set forth and defined therein including, a closure cap fixed to said upper end section and closing the upper 10 end of said cul-de-sac to prevent the entrance of foreign matter and the like therein.

6. The elements of claim 3 as set forth and defined therein including, a closure cap fixed to said upper end section and closing the upper 15 end of said cul-de-sac to prevent the entrance of foreign matter and the like therein.

BASIL NORMAN SMITH.
